UNITED STATES PATENT OFFICE.

ANTHONY E. CARLSON, OF LOS ANGELES, CALIFORNIA.

RAILROAD CROSSING.

1,411,405.

Specification of Letters Patent.

Patented Apr. 4, 1922.

Application filed November 21, 1921. Serial No. 516,803.

To all whom it may concern:

Be it known that I, ANTHONY E. CARLSON, a citizen of the United States, residing at Los Angeles, in the county of Los Angeles and State of California, have invented certain new and useful Improvements in a Railroad Crossing, of which the following is a specification.

My invention relates to improvements in railroad crossings in which the rails cross one another at any angle or curve, in conjunction with double swinging frog members; and the objects of my improvements are, first, to provide a continuous running surface for car wheels to roll over, with clearances for the flange of the said car wheel to pass through; second, to afford facilities for the adjustment or renewal of any worn or broken parts independently of the connecting track-rails leading to the said railroad crossing; and, third, to reduce the pounding of the wheels to a minimum as they roll from one rail to the other on the said crossing at any speed, and to prevent broken rails or flat car wheels.

A further object of my invention is to provide a noiseless crossing which may be manually, mechanically or automatically operated.

I attain these objects by the mechanism illustrated in the accompanying drawing, in which:

Figure 1 is a plan view of my crossing, with a link connection between the companion frogs.

Figure 2 is a plan view of my crossing, with a tooth connection between the companion frogs.

Figure 3 is a sectional view on line 3—3 of Figure 1.

Figure 4 is a sectional view on line 4—4 of Figure 2.

Figure 5 is a sectional view on line 5—5 of Figures 1 and 2.

Referring to the drawings in which like characters of reference designate similar parts, 1 represents a plate with rails 3 and 4 secured thereon, the faces 24 and 23 form the inner sides of the rails 3 and 4 respectively, and may be set to any angle or curve in a railroad crossing, where the same is to be used, the said rails 3 being joined together at their points 25, the two rails 4 being in turn extended in a line adjoining with the said rails 3, the faces 17^b being curved on the inner ends of the said rails, and the said

faces 17^b swinging inwardly on a line joining the outer portion of the rails 4 to the said faces 23 thereon, with the pins 7 as the center of the said curved faces, and the said faces 17^b forming tangents between the said faces 23 and 24. The frogs 2^a and 2^b are operatively secured on the pins 7 between the said faces 24 and 17^b, the pins 7 being secured to the plate 1, and the faces 17^a are curved around the said pins 7 as centers to correspond operatively with the said faces 17^b. The straight faces 10 form the sides of the frogs 2^a and 2^b at points extending from the pins 7 to the faces 17^a. The companion-frogs 12 and 13 are operatively connected to the said frogs 2^a and 2^b respectively by either pins 21 or teeth 28, to form toggle joints therebetween. The faces 11 are formed on the companion-frogs 12 and 13 so as to be positioned at an angle to the faces 23 when the said companion-frogs 12 or 13 are held in a closed position, as shown in Figures 1 and 2, and when the said faces 11 and 23 are positioned parallel to one another the companion-frogs 12 or 13 are held in an open position, as shown in profile in Figure 1. Again, the faces 10 are formed on the frogs 2^a and 2^b so as to be positioned at an angle to the faces 24 when the said frogs 2^a and 2^b are held in a closed position, and when the said faces 10 and 24 are held parallel to one another the frogs 2^a and 2^b are likewise held in an open position. The companion-frog 12 is extended operatively under the companion-frog 13 on the plate 1, and the companion-frog 13 is in turn extended operatively over the companion-frog 12, with the groove 16 positioned flush with the face 17^a, in the frogs 2^a and 13. The sockets 15 and 95 the keys 14 are integral with the inner portions of the said companion-frogs 12 and 13, and mesh together when the said frogs 2^a and 2^b are in their open positions, as shown in profile in Figure 1. The springs 5 are 90 operatively positioned in the plate 1 under the frogs 2^a and 2^b, and are held in their compressed positions by the lugs 6, the said lugs 6 being integral with the said frogs 2^a and 2^b, and extending into the recesses 27, 105 the said recesses 27 being positioned in the plate 1. The levers 22 are operatively connected to the frogs 2^a and 2^b on one end thereof and are in turn connected to an operating means, not shown, on the opposite 110 end thereof.

In the operation of my railroad crossing

the frogs 2^a, 2^b, 13 and 12 are held in their closed positions by the springs 5, thus holding the faces 10 and 11 to the faces 24 and 23 respectively at an angle to one another. 5 and as a car wheel rolls over the rails 3 from either direction towards their points 25 towards the rails 4, the flange on the said car wheel wedges between the faces 24 and 10, and spreads either one of the 10 frogs 2^a or 2^b into an open position, depending upon the direction from which the said wheel is rolling. Thus by spreading the said faces 10 on the frogs 2^a and 2^b, from the faces 24 on the rails 3, an unbroken rolling surface is provided over the rail 3, the frog 2^a and the rail 4, in one direction, and the rail 3, the frog 2^b and the rail 4 in the crossing direction. When the 15 said car wheel is rolling from the opposite 20 direction to those hereinbefore described, beginning from the rails 4, thence over the frogs 2^a or 2^b, to the rails 3, the flange of the car wheel first rolls between the faces 23 and 11, and spreads either the companion- 25 frogs 13 or 12 into open positions, and thus an unbroken rolling surface is provided over the rail 4, the frog 2^a and the rail 3, in one direction, and over the rail 4, the frog 2^b and the rail 3 in the crossing direction. 30

The groove 16 provides a passage for the flange of the said car wheel to pass through when rolling over the frog 2^b.

As a car wheel will only roll from one 35 of the crossing directions over the frogs 2^a and 12, or 2^b and 13, respectively, it will be noted that when the companion-frog 13 is thrown open as hereinbefore described and shown in profile in Figure 1,

the companion-frog 12 is locked in a closed 40 position by the key 14 by meshing into the socket 15, and when the companion-frog 12 is in turn thrown open the companion-frog 13 is likewise locked in a closed position by the key 14 by meshing into the 45 socket 15. The levers 22 throw the frogs 2^a, 2^b, 13 and 12 to their open or closed positions, through the mechanical or manual operating means, not shown.

Having thus described my invention, what 50 I claim is:

1. In a railroad crossing of the class described, a plate support, two joined rails pointed together, two adjoining rails disposed in alignment with the said joined rails, mounted on the said plate, a pair of frogs operatively positioned between the said joined rails and the adjoining rails, respectively, and companion frogs operatively positioned in connection with the said 60 frogs, a locking means integral with the said frogs and companion frogs, as set forth.

2. In a railroad crossing of the class described, a plate support, two joined rails pointed together, two adjoining rails disposed in alignment with the said joined rails, 65 mounted on the said plate, a pair of frogs operatively positioned between the said joined rails and the adjoining rails, respectively, and companion frogs operatively positioned in connection with the said frogs, a locking means integral with the said frogs and companion frogs, an operating means in connection with the said frogs and companion frogs, as set forth. 75

In testimony whereof I affix my signature.

ANTHONY E. CARLSON
